UNITED STATES PATENT OFFICE.

MARCEL A. ROBIN, OF PORT-AU-PRINCE, HAITI, WEST INDIES.

CLEANING DEVICE FOR ABRADING SURFACES.

Application filed August 26, 1926. Serial No. 131,689.

The invention has reference to a device used for reconditioning pencil and ink erasers using abrading material, having particular reference to means for cleaning the abrading surface of detritus left thereon in reconditioning the erasers by abrasive action, and has for its object the provision of means for brushing the abrading surface to remove the particles of rubber and other material left thereon.

Another object is to provide a novel construction wherein the abrader comprises a cover for the device and movement of which will control the position and operation of the abrader-cleaning brush.

Still another object is to provide a construction wherein the abrader has novel means coacting with the brush or its frame to normally prevent movement of the abrader.

Additional objects and advantages will be pointed out and become apparent from a consideration of the description following taken in connection with accompanying drawings illustrating an operative embodiment.

In said drawings:—

Figure 1 is a side elevation of the device; Figure 2 is an end elevation;

Figure 3 is a plan view;

Figure 4 is a longitudinal sectional view through the device showing the abrader detached from the brush frame and its coaction with the latter and brush in the cleaning of the abrader;

Figure 5 is a detail elevation of the brush and its frame;

Figure 6 is a perspective view of the abrader;

Figure 7 is a perspective view illustrating the operating handle for the abrader.

Referring specifically to the drawings, a suitable casing 10 is provided which may have supporting teeth 11, if desired. This casing may be of any approved size and shape, for instance being rectangular as shown and open at the top. The side walls of the casing may be partly removed and provided with windows 12 of suitable transparent material. A suitable drawer 13 is slidably disposed in the casing, being removable through one end thereof and having handles or grips 14 at that end. This drawer 13 is designed to receive material which is removed from erasers when recon-

ditioning the same. The drawer 13 is also open at the top.

Slidably mounted at the top of the casing 10 and covering the same and the drawer 13 is an abrader 15 which may comprise a plate 16 on the upper surface of which an abrading surface is provided in any suitable manner as by gluing a strip of sandpaper or emery paper thereto, the parts preferably being so proportioned that the upper surface of the abrader 16 will be flush with the upper surface of the surrounding walls of the receptacle or casing 10. Midway of its sides, the abrader has a depending can plate 17, extending longitudinally, and having its forward end arranged rearwardly of the forward end of the abrader and preferably inclining upwardly and towards that end.

Depending centrally from the plate 16 are studs 18 and 19, preferably being removably secured thereto in any desired manner. A handle which may be used in reciprocating the abrader is shown in the form of a lever 20 pivoted by a pin 21 to the stud 18. A leaf spring 22 is fastened to the stud 19 and engages the under surface of the lever 20 to normally urge the lever upwardly into engagement with the plate 16. A latch pin 23 extends vertically from the lever 20 forwardly of the plate 16 and rises above that plate.

At the forward corners of the casing 10 bars 24 may be secured as by bolts 25 or any other suitable means. The bars 24 extend a considerable distance above casing 10 and are joined by a tie rod 26 at the top. The facing surfaces of the bars 24 have longitudinal grooves 26^a therein in which side members 27 of a vertically movable frame 28 are slidably disposed. Said frame 28 is completed by a cross rod 29 and the back 30 of a brush 31, parallel thereto and connected to the side members 27. The back of brush 31 is rigid and wire bristles 33 or the equivalent depend therefrom. Rod 29 is disposed at the front of the casing 10 and below the plate 16, which latter overlaps such rod. The frame 28 is urged upwardly, to an extent limited by the engagement of rod 29 with the plate 16, by contractile coil springs 32 fastened to the back 30 and to the rod 26.

Extending rearwardly from the back 30 is a catch member 34 provided with an aperture 35 which may be engaged by the latch 110

pin 23, normally, in order to hold the abrader against movement relatively to the remainder of the device.

The front of drawer 13 is provided with 5 a vertical slot 13^a which accommodates the wall 17 and permits movement thereof.

Normally all of the parts are secured together against relative movement and accordingly the user or operator may hold a 10 rubber or equivalent eraser in his hand and reciprocate or move the same back and forth over the abrasive surface of plate 16, thus removing a portion of the eraser and rendering the latter clean for subsequent use. This 15 action may be followed periodically so that the eraser may be kept clean at all times. The removed matter from the eraser will of course accumulate on the abrader 16 and in order to remove the same, the handle or 20 lever 20 is depressed thus moving pin 23 out of the aperture 35, releasing the abrader 16 so that it may be pulled toward the operator. As the forward end of the cam plate 17 is spaced from the forward end of the 25 plate 16, the brush 31 will not be moved until the pin 23 is at a distance from the plate 34. Outward movement of the handle 20 and plate 16 gradually moves the cam plate 17 into engagement with the rod 29, 30 thus depressing or moving frame 28 downwardly and causing the bristles 33 to engage the sandpaper or abrading surface of the plate 16 so that the material accumulated thereon will be brushed therefrom or removed into the drawer 13 which becomes exposed of course as the plate 16 is moved outwardly. The drawer 13 may be emptied at 35 desired times.

One or more contractile springs 36 may 40 be fastened to casing 10 and the abrader to urge the latter to drawer-closing position.

It will be understood that the device hereinbefore described may be used not only to clean rubber erasers but also to sharpen them for efficient erasure of letters in type-written copies.

I claim as my invention:—

1. A device of the class described comprising a casing, a drawer therein, an abrader constituting a cover for the casing and drawer movable relatively thereto whereby abraded material may be removed from the abrader into the drawer, means on the casing to effect such removal, and means to connect the abrader to the first mentioned to hold it in covering position.

2. A device of the class described comprising a casing, an abrader constituting a cover therefor and movable relatively thereto, a brush to remove abraded material from the

abrader into the casing, and means to move said brush to operative position through movement of the abrader.

3. A device of the class described comprising a casing, an abrader constituting a cover 65 therefor and movable relatively thereto, a brush to remove abraded material from the abrader into the casing, means to move said brush to operative position through movement of the abrader, and means to secure the 70 abrader to the brush to hold it in covering position.

4. A device of the class described comprising a casing, an abrader serving as a cover therefor and movable relatively thereto, a frame mounted to slide toward and from the abrader, a brush carried by the frame to engage the abrader to remove material therefrom into the casing, and, the abrader having a cam plate depending therefrom and directly engaging the frame to move the brush into engagement with the abrader.

5. A device of the class described comprising a casing, an abrader serving as a 85 cover therefor, a frame movable through movement of the abrader, a brush carried by the frame to engage the abrader to remove material therefrom into the casing through said movement, a lever on the abrader constituting a handle therefor, and means on the lever coacting with the frame to normally secure the abrader against movement relatively to the casing.

6. A device of the class described comprising a casing, a drawer therein provided with a slot in an end wall thereof, a plate forming an abrader and covering the casing and drawer, said plate having a depending cam plate movable through said slot, 100 studs depending from the plate forwardly of the casing and drawer, an operating lever pivoted to one of the studs, spring means secured to the other stud and urging upward movement of the lever, a latch pin on 105 the lever, bars rising from the front corners of the casing, said bars having grooves in their facing surfaces, a frame slidable in said grooves and including a cross rod disposed below the plate, a brush carried by 110 the frame above the plate and having a rearwardly extending catch engageable by said pin to normally hold the plate against movement relatively to the casing, and said cam plate being engageable with said rod to depress said frame and move the brush into engagement with the plate to remove abraded material therefrom into the drawer.

In testimony whereof I affix my signature.
MARCEL A. ROBIN.
